ROOFING CONSTRUCTION

Ayana L. Wall, Cleveland, Ohio

Application July 24, 1937, Serial No. 155,500

2 Claims. (Cl. 108—7)

This invention relates to roofing construction elements and roofings made therefrom, and more particularly to the construction of roofing elements such as shingle strips comprising a base sheet of felt or like fibrous material saturated with liquid bitumen, such as asphalt.

As these strips are ordinarily constructed, a coating of asphalt, or similar adhesive and waterproofing material, is applied to the top of the strip, and granules of slate or similar material are embedded in this coating for the purpose of increasing the weather-resisting qualities of the product. Where ornamentation is desired, this result may be secured by using colored granules.

As usually constructed, the shingle strips present a flat and unattractive appearance when laid upon a roof. It is the general purpose and object of my invention to impart a more pleasing appearance to these strips; to increase the strength, rigidity, and wearing qualities thereof; and to enable the exposed portions the better to withstand the effects of weather and the lifting effects of the wind.

I accomplish these objects in and through the construction of a special form of so-called thick-but shingle strips, which will be described in connection with the accompanying drawing, wherein Fig. 1 shows a section of a roof made up of composite strips embodying my invention; Fig. 2 is a plan view of one of the shingle strips shown in the preceding figure; and Fig. 3 is an enlarged detail in section taken on the line 3—3 of Fig. 2, the position of the lower portions of strips in the courses above being indicated by dot-and-dash lines and showing the location of one of the nailing lines.

Describing by reference characters the various parts illustrated in the drawing, 1 denotes a sheet of fibrous material, such as felt, saturated with liquid bitumen, as asphalt. Applied to the upper surface of this sheet is a coating 2 of adhesive material, preferably asphalt, having embedded therein granules 3 of sand or similar material. 4 denotes another coating of similar adhesive material applied to and entirely covering the coating 2 and having embedded therein granules 5 of slate or similar material.

6 denotes a coating of asphalt or similar adhesive material which is applied to and which completely covers the under surface of the sheet 1, the said coating having finely divided mica particles 7 applied thereto and embedded therein. 8 denotes another coating of asphalt or similar adhesive material which is applied to the bottom of the coating 6, 7 and which extends from the lower

end of the strip approximately half the height or width of the same. This coating has particles of granular material, such as slate, applied thereto and embedded therein, as indicated at 9.

Each of the strips as thus constructed is provided with slots 10 extending upwardly from the bottom edge thereof and terminating below the upper end of the coating 8, 9. In practice, in strips having a height or width of 12 inches, the coating 8, 9 extends upwardly about 6 inches from the bottom of the strip while the slots 10 extend upwardly approximately 5 inches. This will enable the bottom of a strip 11 in the next upper course to extend downwardly as far as the tops of the slots in the next lower course and provide at the same time a covering for the nails 12 by which the strips in such lower courses are secured to the roof frame. It will be noted further that, when the strips are nailed in the usual manner—at a short distance above the tops of the slots 10—the nails will not only be covered by the bottoms of the strips in the next course above, but will be driven through the thickest and strongest portion of each strip, as will be evident from Fig. 3, wherein one of the nails is indicated at 12.

The thickness of the coating is exaggerated in the drawing for purposes of illustration, and the exposed lower ends of the tabs in Figs. 1 and 2 are not stippled to indicate the granules 5.

It will be noted that a step is provided between the coating 8, 9 and the coating 6, 7, this step being covered by the butt or butts of the shingle or shingles in the next course above. Because of this construction, the lower ends of the shingles will hug tightly the roof and the tops of shingles in subjacent courses and will offer greater resistance to the lifting effect of the wind than if the steps were provided upon the upper surfaces of the shingles.

In virtue of my invention, I am enabled to produce roofing having not only all of the advantages due to the use of the ordinary type of thick-but shingles or shingle strips, but also the advantages of extra strength and rigidity throughout the thickened portion thereof, together with extra wearing qualities and enhanced beauty of appearance.

It is obvious that my invention is applicable to and may be embodied in individual shingles as well as in elongated shingle strips having tabs which simulate the exposed ends of individual shingles. Hence the term "strip" as used in the specification and claims hereof is intended to cover a strip constituting an individual shingle.

as well as a longer strip having a plurality of tabs, except where the latter type of strip is specifically identified by limitations peculiar thereto.

Having thus described my invention, what I claim is:

1. A roofing element comprising a strip of saturated fibrous material having a coating of adhesive material and granules applied to the upper surface thereof and entirely covering the same,
- 10 a second coating of adhesive material and granules applied to the upper surface of the first coating and entirely covering the same, a third coating of adhesive material and finely divided granular material applied to and entirely covering the lower surface of the said strip, and a fourth coating of adhesive and granular material applied to the third coating and extending from the bottom of the strip toward but terminating short of the top thereof.
- 15

2. A roofing element comprising a strip of saturated fibrous material having a coating of adhesive material and granules entirely covering the upper surface thereof, a second coating of adhesive material and granules applied to the upper surface of the first coating and entirely covering the same, a third coating of adhesive material and finely divided granular material applied to and entirely covering the lower surface of the said strip, and a fourth coating of adhesive and granular material applied to the third coating and extending from the bottom of the strip toward but terminating short of the top thereof, the said strip being provided with slots extending upwardly from the bottom edge thereof to form tabs, the tops of the slots being located below the top of the fourth coating.
